UNITED STATES PATENT OFFICE

2,505,386

FLUID PUMP

Howard C. Collins, Molalla, Oreg.

Application March 23, 1946, Serial No. 656,649

1 Claim. (Cl. 103—89)

1

This invention relates to an improved fluid pump of the archimedean screw type, particularly adapted for continuously impelling water as required in mining and irrigating systems.

An object of the invention is to provide an efficient and durable pump of the above kind which may be constructed at low cost.

A more specific object of the invention is to provide an improved arrangement of stuffing boxes and bearings for the shafts of the screw impeller, whereby to facilitate adjustment of the glands of the stuffing boxes so as to minimize leakage of water from the pump cylinder about such shafts, and whereby to provide for efficient lubrication of the bearings.

The exact nature of the present invention, as well as more specific objects and features thereof, will become apparent from the following description when considered in connection with the accompanying drawings, in which:

Figure 1 is a side elevational view of a fluid pump constructed in accordance with the present invention.

Figure 2 is a top plan view thereof.

Figure 3 is a central vertical longitudinal section taken on line 3—3 of Figure 2.

Figure 4 is a view similar to Figure 3 taken on line 4—4 of Figure 2.

Referring in detail to the drawings, the present pump comprises a casting which includes an elongated pump cylinder 5 having integral top inlet and outlet pipes 6 and 7, respectively, near opposite ends thereof, and an integral extension 8 on one end of the cylinder projecting beyond the juncture of the outlet pipe 7 with the cylinder. The pipes 6 and 7 diverge upwardly, the inlet pipe 6 being of greater size and capacity than the cylinder 5 and the outlet pipe 7 being of smaller size and capacity than the cylinder 5.

A second extension 9 is detachably joined at 10 to the other end of the cylinder 5 and projects beyond the juncture of the inlet pipe 6 with said cylinder. An inclined deflector plate 11 is fitted and welded or otherwise secured in the end of the cylinder 5 adjacent the outlet pipe 7 for directing the fluid from the cylinder 5 into said outlet pipe. Removable closure caps 12 and 13 are provided on the outer ends of the extensions 8 and 9.

A screw impeller 14 having at least one continuous helical rib 15, is rotatably fitted in and extends substantially from end to end of the cylinder 5. This impeller has axial shafts 16 and 17 on the ends thereof that extend axially of the extensions 8 and 9.

Spaced inner and outer stuffing boxes 18 and 19 for each of the shafts 16 and 17 are fitted and secured in the associated extension so that their glands 20 and 21 are adjustable from adjacent ends thereof. Each extension has a covered top hand hole 22 to facilitate access to the stuffing boxes for adjustment of the glands thereof, the covers of said hand holes being indicated at 23.

Each extension also has a bottom water drain 24 at a point between the stuffing boxes therein. This provides for drainage of water that may pass through the inner stuffing boxes 18 and minimizes the passage of water through the outer stuffing boxes 19, which water may leak from the pump cylinder about the shafts 16 and 17.

Bearings of the combined radial and thrust type may be provided for the shafts 16 and 17 in the outer ends of the outer stuffing boxes 19 as indicated at 25. The outer stuffing boxes 19 are spaced from the closure caps 12 and 13 so as to provide spaces therebetween for reception of lubricant for the bearings at 25. Means is provided at 26 and 27, respectively, to facilitate introduction of lubricant into and drainage of the same from the spaces between the outer stuffing boxes 19 and the closure caps 12 and 13.

The shaft 17 projects through the adjacent closure cap 13 so as to facilitate driving thereof for effecting rotation of the impeller. Motion is preferably transmitted to the shaft 17 from a drive shaft 28 through an encased increase-speed gearing 29. A suitable grease retainer 30 may be provided to prevent leakage of lubricant through the cap 13 about the shaft 17.

In operation, the impeller 14 is driven at the desired speed so as to draw the water into cylinder 5 through inlet 6 and forcibly discharge the water from said cylinder into and through the outlet pipe 7. Due to the reduced size of the cylinder relative to the inlet and the reduced size of the outlet relative to the cylinder, the pump is adapted to pump the water against a relatively large head of water.

From the foregoing description, it is believed that the construction, operation and advantages of the invention will be readily understood and appreciated by those skilled in the art. Minor changes are contemplated, such as fall within the scope of the invention as claimed.

50 What I claim is:

A liquid pump comprising an elongated horizontal pump cylinder having upwardly diverging cylindrical top inlet and outlet pipes near opposite ends thereof, an inclined baffle secured in 55 the pump cylinder to direct the liquid from the

latter into said outlet pipe, said inlet and outlet pipes being respectively of larger and smaller diameter than said cylinder, a tubular cylinder extension detachably joined to the end of said cylinder near the inlet pipe, pairs of spaced stuffing boxes in said cylinder extension and in the other end of said cylinder, removable closure caps on said other end of the cylinder and the outer end of said cylinder extension, means to facilitate access to the space between the stuffing boxes of each pair respectively through the top of the cylinder and through the top of the cylinder extension, a screw impeller rotatably fitted in the cylinder and extending from the inlet pipe to the outlet pipe, said impeller having end shafts extending through said stuffing boxes, one of said shafts extending through the closure cap of said cylinder extension for connection with driving

means, and means to drain water from the space between the stuffing boxes of each pair.

HOWARD C. COLLINS.
